Application December 23, 1947, Serial No. 143,306

Term of patent 7 years

(Cl. D86—10)

To all whom it may concern:

Be it known that I, Ladislas Medgyes, a citizen of the United States of America, residing at 2 East 56th Street, New York city, in the county of New York and State of New York, have invented a new, original, and ornamental Design for Nail Polish Bottle Holder and Finger Rest, of which the following is a specification, reference being had to the accompanying drawing, forming part thereof.

In the drawing:

Fig. 1 is a top plan view of a nail polish bottle holder and finger rest, showing my new design;

Fig. 2 is a side elevational view of the same, and

Fig. 3 is a substantially transverse sectional view taken on lines 3—3 of Figure 1.

I claim:

The ornamental design for a nail polish bottle holder and finger rest, as shown.

LADISLAS MEDGYES.
